UNITED STATES PATENT OFFICE.

HARRY G. PORTER, OF CHICAGO, ILLINOIS, ASSIGNOR TO WILLIAM F. DEUSS, OF CHICAGO, ILLINOIS.

INDEX-TAB STRIP.

1,326,370.

Specification of Letters Patent.

Patented Dec. 30, 1919.

Application filed January 2, 1919. Serial No. 269,236.

To all whom it may concern:

Be it known that I, HARRY G. PORTER, citizen of the United States, residing in the city of Chicago, Cook county, Illinois, have 5 invented certain new and useful Improvements in Index-Tab Strips; and I do hereby declare the following to be a full, clear, and exact description of the invention, such as will enable others skilled in the art to 10 which it appertains to make and use the same.

My invention relates to a mounting or carrier for index tabs, and to the method of making the same. Heretofore, index tabs 15 of the kind used on the leaves of ledgers or the like have sometimes been stored and packed for shipment in compartmental boxes, the tabs being all completely cut and ready for attachment to the sheets, and the 20 tabs bearing each particular letter or other character being sorted into one compartment. When thus put up, it has been difficult to keep them from getting mixed in shipment, or to prevent breaking the completeness 25 of the sets by the loss of one or more tabs. It has also been difficult to secure a proper matching of the color of the leather or other fabric when securing the tabs in proper arrangement to the leaves 30 of a ledger or the like, as the tint of the leather is apt to vary considerably.

To overcome some of these difficulties, it has also been customary to ship and store the tabs either in uncut strips, or in strips 35 cut only part way through between the successive characters, thereby securing uniformity of tint of the fabric; but either compelling the user to employ some tool for completely separating the individual tabs 40 from the strip, or else leaving rough edges and even projecting threads in case the separation was finished by a tearing operation. My invention aims to avoid the objections to both of the above described 45 methods, by providing a simple mounting or carrier for completely manufactured index tabs, so as to hold a series of such tabs together in the form of a strip, while still permitting each individual tab to be speedily 50 detached without the use of any tool and without in any way damaging the tab. More particularly, my invention aims to provide an inexpensive and cheaply made carrier adapted to hold one or more groups of 55 tabs in suitable order and adapted to hold

the individual tabs in such perfect alignment as not to present projecting portions adapted to catch on adjacent tabs or other objects when the assemblage is handled. Furthermore, my invention aims to provide 60 an exceedingly simple and inexpensive method of manufacturing and attaching such a carrier and of completing the separation of the individual tabs after they are attached to the carrier in the desired order; 65 also, to so mount the individual tabs on the carrier that during the manual detaching, each tab will be grasped in a most convenient position for moistening the gumming on the same and for applying the tab to the sheet to 70 which it is to be attached, thereby saving both the labor and time involved by the repeated handling of tabs as required with the tab-strips heretofore on the market.

In another aspect, my invention aims to 75 provide means for attaching advertising matter to index-tabs, so as to utilize the advertising possibilities afforded by distributing such tabs to widely scattered users through dealers in book-binders' supplies. 80 Where index-tabs have been put up according to the old methods, this has not been possible, as the inner surfaces of the tab flaps are both gummed and normally concealed, while the outer surface portions of 85 the tabs are exposed on the sheets to which they are to be attached and therefore should not be marred by affixing any extraneous matter. Still further objects will appear from the following specification and from 90 the accompanying drawings, in which drawings—

Figure 1 is an elevation of a duplex tab-strip embodying my invention and having tabs attached along two of its opposite 95 edges.

Fig. 2 is an enlarged transverse section through the tab-strip of Fig. 1 showing the carrier as gummed flatwise to one of the flap portions of an index tab.

Fig. 3 is a similar section through a one-sided tab strip, showing a somewhat heavier carrier sheet gummed at its edge to the edge of the filler in an index tab.

Fig. 4 is a fragmentary elevation of a carrier sheet, indicating two methods of moistening the same for attaching the sheet to index tab-strips according to the method of my invention.

Fig. 5 is a perspective view showing how 110

the article of my invention can conveniently be handled in the detaching of individual tabs from the same.

In manufacturing tab-strips according to my invention, the consecutively lettered or otherwise designated carrier portions are first made in uncut strips after the manner heretofore in use, namely in the form of a strip of leather or other suitable material 5 doubled medially upon itself and having the portions near the edge of the fold rigidly secured to each other and desirably having a stiffening filler 1 interposed between these portions. Before making the tab strip in 10 this uncut form, the inner faces of the flap portions 2 which extend from the rear edge of the filler to the free edges of the strip are suitably surfaced with glue, so as to be ready for attaching them to the opposite 15 sides of a ledger page or the like by merely moistening them. I then take a sheet 3 of paper, cardboard or other suitable material, partially moisten the same, and insert the moistened portion between the inwardly 20 gummed and relatively unattached flap portions of the tab-strip, the sheet used being of such width as to project for some distance 25 beyond the free rear edges of the tab strip.

With the sheet in this position, I cut 30 transverse incisions between the individual marked portions of the tab strip, these incisions extending to such a distance from the fold edge of the tab strip as to extend across the entire width of the tab-strip and 35 through that portion of the carrier sheet which is interposed between the free flap portions of the tab-strip. This cutting operation is quickly and cheaply performed by means of suitably spaced knives mounted 40 in a chase, and in practice the power exerted during the cutting will force the flap portions of the tab-strip against the carrier sheet with sufficient pressure to cause the moistened portions of the sheet to adhere 45 to the adjacent gummed or glued-surface parts of the leather. Consequently, when the parts as thus described are removed from the cutting portions, they will comprise a series of completely manufactured 50 index-tabs, cut entirely apart, with each tab gummed to a finger formed by the cutting of the incisions through the interposed portions of the carrier sheet. The gumming required for this purpose need only cover a 55 quite small portion of the area of one of the inwardly gummed flaps, hence I have found it ample with the process of manufacture either to moisten the carrier sheet along a narrow strip as shown at the left 60 hand of Fig. 4, or to moisten this sheet in small spots successively spaced from each other according to the width of the proposed tabs, as shown at the right hand of Fig. 4.

65 In either case, the simple method of

manufacture as above described will leave the completely cut index-tabs attached to only such a limited extent that they can readily be snapped off or pulled off the carrier sheet by hand. In doing this, a number of tabs can be removed simultaneously if desired. Or, each tab can be grasped separately, approximately as shown in Fig. 5. When thus grasped, it will be obvious from this part of my drawings, that the tab 70 is held in convenient position for pressing the gummed inner faces of the flaps against a sponge or other moistening surface and for thereafter affixing these flaps to a ledger page, card index sheet or the like. Consequently, each individual tab can be manipulated from its position on the carrier sheet 75 to its service position with a single grasping of the index-tab, thereby saving considerable time and labor over that required 80 with tab-strips as heretofore offered on the market.

At the same time, by attaching the initial and uncut tab-strip to the carrier sheet before making the incision, I insure a uniform texture of the leather or other tab material for the whole series, and also insure an accurate alinement of the fold edges of the individual tabs, so that the resulting article of manufacture will not present irregular or rough edge portions adapted to catch on other objects. The completely manufactured article therefore presents a handsome appearance, permits of speedy and convenient handling without danger of 90 damaging the individual tabs, and yet saves labor over both the partly cut tab-strips heretofore used and also over the compartmental assortments, as the latter arrangement leaves the individual tabs in all sorts 95 of positions, so that they have to be turned and straightened and resorted from one compartment to another.

Since the uncut portion of the carrier-sheet is exposed when my article of manufacture is completed, this portion offers a suitable medium for carrying advertising legends, and, if desired, these legends may even extend to the fingers of the sheet as shown in Fig. 5. Thus, every tab carrier 100 can be utilized for conveying advertising information.

However, while I have described my invention as including tabs having a main folded portion of leather, and gummed flatwise to one of the flaps or such leather, I do not wish to be limited either to the materials described or to other details of the construction and arrangement here disclosed, it being obvious that the same might 110 be varied in many respects without departing from the spirit of my invention. For example where a relatively thick filler is used in the tabs, the carrier sheet may be 115 gummed edgewise to the rear edge of the 120

filler itself as illustrated in Fig. 3. So also, the tabs may be affixed either to both edges of the carrier (as in Figs. 1 and 2) or along only one edge, as in Fig. 3.

5 I claim as my invention:

1. The combination with index tabs each including a piece of sheet material folded upon itself and having the edge portions of the resulting flaps free from each other, 10 of a carrier having fingers each overlapping a flap of an individual tab, each of the fingers being so secured to the flap overlapped thereby as to be manually detachable from the latter.
- 15 2. In combination with index tabs each including a strip of sheet material doubled upon itself and having the edge portions of the resulting flaps free from each other, of a carrier having fingers of the same width 20 as the tabs, each finger of the carrier being interposed between the two flaps of a single tab and lightly gummed to one of the said flaps.
- 25 3. The combination with index tabs, each of which comprises a stiffening filler and a strip of sheet material folded over and secured to the stiffening filler and presenting flap portions extending laterally beyond the filler and free from each other, of a carrier 30 having separated portions each secured to a laterally extending flap portion of a single tab, the said carrier also having a portion projecting beyond the said flaps and connecting the said separated portions of the 35 carrier.
4. The method of mounting and completing the manufacture of index tabs, which consists in interposing between the flaps of an uncut tab-strip a portion only of the width 40 of a sheet of material, gluing the interposed sheet portion for a part only of its inter-

posed surface to one of the flaps, and separating the individual tabs by incisions extending through the entire width of the tab strip but not extending entirely through 45 the said sheet.

5. The method of mounting and completing the manufacture of index tabs from uncut tab-strips having glued surfaces on the opposed flaps of the tab-strips, which consists in moistening a portion only of a sheet of suitable material, interposing the moistened portion between the flaps, and thereafter cutting transverse incisions entirely through the flaps but only part way through 50 the said sheet while exerting sufficient pressure to cause the moistened sheet portions to attach themselves to the glued tab portions facing the same.

55 6. The method of making an index-tab strip which consists in first affixing a carrier strip to a group of index-tabs in such a manner that a portion of the carrier strip will project beyond all of the tabs, and then making incisions entirely severing the index-tabs from each other but leaving each still attached to a part of the carrier.

7. A combined index-tab carrier and advertising medium comprising a series of tabs, and a sheet having fingers secured respectively to individual tabs and having a portion connecting the said fingers and bearing an advertising legend.

75 8. As a new article of manufacture, a carrier strip having a legend-bearing portion and a plurality of relatively separated fingers at one side of the said portion, and index-tabs respectively and detachably carried by the said fingers.

Signed at Chicago, Illinois, December 30 30th, 1919.

HARRY G. PORTER.
